DOUBLE COMPARTMENT NESTING BAND PACKAGE

Filed Dec. 10, 1947

UNITED STATES PATENT OFFICE

2,529,837

DOUBLE COMPARTMENT NESTING BAND PACKAGE

William E. Denison, Chicago, Ill., assignor to
Tammen and Denison, Inc., Chicago, Ill., a corporation of Illinois

Application December 10, 1947; Serial No. 790,791

12 Claims. (Cl. 99—171)

1

This invention relates to a double compartment, nesting band package. It is a continuation in part of applicant's copending applications, Serial No. 774,013, filed September 15, 1947 and Serial No. 780,120, filed October 16, 1947.

The object of this invention is to provide a package for holding two materials that are to be mixed by the user in separate compartments from the time that the package is first prepared by the manufacturer to the time that the user is ready to mix. The specific materials with which applicant is dealing are oleomargarine and coloring. The central idea of the invention turns on the use of two nesting bands or rings each of which engage one wall of the wrapper and by being nested form a compartment between the two walls of the wrapper inside the rings or bands.

The two embodiments of the invention are illustrated in the drawings. The first embodiment is shown in Figs. 1 and 2, being perspective views of the package and an enlarged sectional view of two nesting plates. This was the original conception. The second embodiment of the invention is the preferred embodiment and is illustrated in perspective as two nesting, plastic or metal bands in Fig. 3, while Fig. 4 is a sectional view assembled on a container. Fig. 5 shows the rings pressed against the print preparatory to cartoning; and Fig. 6 shows a relationship of the bands to the sealed end of a container that may be adopted.

Continuing to refer to the drawings, numeral 10 identifies a package made of heat-sealable material having a longitudinal seal 12 and end seals 14 and 16. The earlier-filed application discloses the method for forming such a package. A print of oleomargarine 18 is shown positioned in the package closer to the left end than to the right end so as to provide usable lengths of top and bottom (and side) walls between the print and the transverse heat seal 16.

A pair of complementary nesting plates 20 and 22 are illustrated in Fig. 2. The plate 20 has a flat peripheral surface 24 for engaging the flat surface of the wrapper, which in this case is vinylite or pliofilm, and a centrally depressed portion 26. This portion 26 is joined to the flat peripheral surface by an integral wall 28 which may have an outwardly directed bead 30. The plate is a stamping made of either metal or plastic and it is somewhat costly to form the bead. The lower plate 22 has an upwardly directed wall 32 with a constriction 34 and a flat peripheral surface 36 engageable with the under side of the flat peripheral surface 24.

2

One plate is moved downwardly against the top wall of the package 10 and the lower plate is moved upwardly against the lower wall and when the two plates are nested, they squeeze between themselves two portions of the wall of the package identified by the numerals 38 and 40. Between the two walls 38 and 40 is positioned coloring material 39, and for the method of positioning the coloring material, see the earlier-filed copending application, Serial No. 774,013, filed September 14, 1947.

The embodiment of the invention that is likely to go into commercial use is illustrated in Figs. 3 and 4. It consists of two nesting bands or rings 42 and 44. These bands 42 and 44 are brought into engagement with the package to form a compartment for the coloring in the same manner as are the nesting plates. The nesting bands really constitute nothing more than a removal of the flat peripheral surfaces 24 and 36 and the central portions of the plates 20 and 22. It has been found that the engaging walls of the bands 42 and 44 will hold the walls of the container sufficiently tightly so that the coloring material 39 cannot work into the oleomargarine and conversely, the oleomargarine cannot work into the coloring material. The bands have the advantage that they can be inexpensively made. They lend themselves to the employment of plastics, and as these may be obtained in many colors, very attractive packages are possible. In Fig. 5, applicant has illustrated how the bands package has its ends pressed up together with the brick so that it fits snugly in a standard Western-type carton. Because the wrapper is transparent, the oleomargarine appears in its natural color, namely white, and the employment of green, red, yellow or blue bands not only presents a pleasant contrast, but draws to the housewife's attention the portion of the package which she must first act upon in order to perform the mixing operation.

The bands have another advantage over the nesting plates in that the coloring can be plainly seen between the transparent walls of the wrapper. This is thought by sales departments to be a distinctive feature.

In order to use, all a housewife need do is unnest the bands. In the case of the plates, there are provided tongues, such as 46 which is in vertical alignment with a similar tongue, not shown, on the lower plate 22. A fingernail can be inserted between the tongues to unnest the plates.

The package here shown is made of a strong, flexible material so that it can be kneaded for

mixing purposes, and is completely sealed. However, there are many applications in the packaging field where these nesting bands would be useful on packages which are made of a weaker material but which are sealed so that they can be manipulated or shaken to mix two ingredients. Thus, there are washing compounds formed of washing powder and a bleach powder which should be maintained separate until used by a consumer and nesting bands could be used to form the separate compartments.

It will be appreciated that the amount of wall on the package that is inside the nesting bands can be varied to provide a much greater volume in those cases where the second material has a greater volume. In the case of the oleomargarine and coloring, the volume of coloring as compared to the volume of the oleomargarine is comparatively small, and hence, the coloring compartment need provide very little volume, as is illustrated in Fig. 4.

The peripheral configuration of the nesting bands is not critical. It is important that they nest and that they form between the inside surfaces of the package walls a continuous wall, at least, a continuous wall adjacent that part of the enclosure which contains the other material, in this instance, the oleomargarine. There is a strong likelihood that in the commercial package, only a portion of the engaging surfaces of the bands will separate the coloring compartment from the oleomargarine. In Fig. 6, the coloring end of the package may be shaped like a tongue with a comparatively wide heat-seal indicated by the shaded lines 48 and the bands will be seated as shown. The coloring is at 50 and only those portions of the bands between the arrows 52 and 54 will actually separate the coloring material from the oleomargarine compartment.

The use of these nesting bands is of great value in the method of making the package. This method, as described in the copending application, comprises the steps of advancing a web of vinylite horizontally through a series of work-performing stations; of depositing on the moving web alternate prints of oleomargarine and spots of coloring in spaced relationship; of wrapping the two side edges of the web over the oleomargarine print and sealing the edges to each other to form a tube; of transversely sealing the tube between the rear side of a print and the spot of coloring; and of then applying some kind of an external holding means to the walls of the package between the coloring material and the oleomargarine print. This last step is the critical step because applicant's method and the machine that he is designing is intended to operate at a speed of sixty packages a minute. Separating each package into two compartments must, therefore, be fast and sure. Anything that can be done to avoid a walking or moving station on the packaging line at this point is of great value. It is thought that these bands offer great possibilities in the method because they can be applied almost instantaneously. If registration of the applying means with the coloring spot is attained, the band-applying mechanism can function so quickly that it may be possible for it to work even though it is stationary and the tube of articles is moving. If this is not possible, it does seem clear that the band-applying mechanism will have to move only a short distance with the moving web.

Having thus described my invention, what I claim is:

1. A package for holding separate two materials until received by the user comprising an envelope having flexible walls, a band engaging the outside surface of a portion of one wall, and a nesting band engaging the outside surface of a portion of an opposite wall and frictionally seated in the first band so as to form a compartment between the walls of the package lying within and on the same side of the nesting bands and separate from the compartment formed between the remaining portions of the walls of the envelope.

2. A sealed package for holding separate two materials to be mixed by manipulation of the package by the user comprising a sealed envelope having walls, a band engaging the outside surface of a portion of one wall, and a nesting band engaging the outside of a portion of an opposite wall and frictionally seated in the first band so as to form a compartment between the two package walls confined within and on the same side of the two bands and separate from the compartment formed between the remaining portions of the walls of the envelope.

3. A sealed package for holding separate two kneadable materials until kneading is performed by the user comprising a sealed envelope of sturdy, flexible material having walls, a band engaging the outside surface of a portion of one wall, and a nesting band engaging the outside surface of a portion of an opposite wall and frictionally seated in the first band so as to form a compartment between the package walls confined on the same side of and by the nesting bands and separate from the compartment formed between the remaining portions of the walls of the envelope.

4. A package for holding separate two mixable materials until received by the user comprising an envelope having walls, a charge of one material in one portion of the envelope, a band engaging the outside surface of a wall of the envelope not adjacent to the charge, a nesting band engaging the outside surface of an opposite wall likewise not adjacent to the charge and frictionally seated in the first band, and a charge of a second material positioned between the two package walls lying within the enclosure of the nesting bands and on the same side of the bands.

5. A sealed package for holding oleomargarine and coloring separate until kneaded into a homogeneous compound by the user comprising a sealed envelope of sturdy, flexible material, a charge of oleomargarine in one portion of the envelope, a charge of coloring material in another portion of the envelope and spaced from the oleomargarine, a band engaging the outside surface of a package wall adjacent and around the coloring, a nesting band engaging the outside surface of an opposite wall and frictionally seated in the first band so as to confine the coloring in a compartment separate from the oleomargarine.

6. A package for holding separate two mixable materials until received by the user comprising an elongated envelope having walls, a charge of one material in one end of the package, a charge of a second material in the other end of the package and spaced from the first material, a band engaging the outside of a wall of the package adjacent and around the second material, and a nesting band engaging the outside surface of an opposite wall and frictionally seated in the first band so as to form a compartment around the second material into which the first material does not penetrate.

7. The package of claim 1 wherein each band has a central plate integrally formed with its periphery.

8. The package of claim 7 wherein each plate band has a laterally extending tongue at the same point on its periphery to facilitate separation of the plates from each other.

9. The method of forming a multiple compartment container which comprises the steps of positioning in spaced relationship within a single 10 enclosure two materials, and of joining the opposite walls of the enclosure around one material by nesting a band engaging the outside surface of one wall in a band engaging the outside surface of an opposite wall.

10. The method of forming a multiple compartment container which comprises the steps of positioning two materials in spaced relationship on a wrapper, of wrapping the edges of the wrapper around the two materials into engagement with each other and sealing them to form a tube with the two materials spaced from each other, of transversely sealing the edges of the wrapper to form a sealed enclosure, and of seating nesting bands respectively over the opposite walls of the wrapper adjacent one of the materials so as to confine that material within walls bounded by the seated bands.

11. The method of forming multiple compartment containers which comprises the steps of moving a web of wrapping material horizontally, of depositing on said web in spaced relationship

successive alternate charges of two different materials, of drawing the side edges of the web over the materials and sealing them to each other to form a tube, of transversely sealing and severing the tube between a charge of one material and that charge of the other material which is to be associated with another charge of the first material, and of seating nesting bands in each other over the opposite walls of the wrapper adjacent one of the materials so as to confine that material within walls bounded by the seated bands.

12. The method of claim 11 wherein the web is a sturdy, flexible transparent material and wherein the two materials packaged are oleomargarine and coloring respectively.
